(57) **CLAIM**

The ornamental design for an appliance wheel placement chock, as shown and described.

DESCRIPTION

FIG. 1 is a top perspective view of the appliance wheel placement chock according to the present disclosure.

FIG. 2 is a top view of the appliance wheel placement chock according to the present disclosure.

FIG. 3 is a bottom view of the appliance wheel placement chock according to the present disclosure.

FIG. 4 is a right side view of the appliance wheel placement chock according to the present disclosure.

FIG. 5 is a left side view of the appliance wheel placement chock according to the present disclosure.

FIG. 6 is a front view of the appliance wheel placement chock according to the present disclosure; and,

FIG. 7 is a back view of the appliance wheel placement chock according to the present disclosure.

The broken lines shown in the drawings represent unclaimed portions of the appliance wheel placement chock and form no part of the claimed design.
